FIG. 10

Attorney

UNITED STATES PATENT OFFICE.

LAURENCE WILLIAM JERNBERG, OF WORCESTER, MASSACHUSETTS.

FURNACE-GRADE.

SPECIFICATION forming part of Letters Patent No. 469,816, dated March 1, 1892.

Application filed August 14, 1891. Serial No. 402,603. (No model.)

To all whom it may concern:

Be it known that I, LAURENCE WILLIAM JERNBERG, a citizen of the United States, residing at Worcester, in the county of Worcester and State of Massachusetts, have invented a new and useful Furnace-Grate, of which the following, together with the accompanying drawings, is a specification sufficiently full, clear, and exact to enable persons skilled in the art to which this invention appertains to make and use the same.

This invention relates to improvements in that class of furnace-grates wherein a series of independent bars are separately supported on struts or tilting chairs, thereby affording facility for easy endwise movement of the bar.

The objects of my invention are, first, to provide improved means for effecting the shaking action of the grate, adapted for large or small grates and whereby large and heavy furnace-grates can be operated with ease and facility; second, to provide a peculiar construction of stilt-bar or tilting chair which will afford support for the bars against lateral displacement; third, to provide, in combination with the ends of the bars, a system of peculiarly-arranged finger-plates or end guards that can be individually readily removed to facilitate the removal of any grate-bar; fourth, to provide a grate-bar which works in connection with the end guard by a lifting and endwise action, and having downwardly-curved ends to prevent the blocking of the grate-bars by clinkers or pieces of coal. These objects I attain by the mechanism herein shown and described, the particular subject-matter claimed being hereinafter definitely specified.

In the drawings, Figure 1 is a vertical longitudinal section through my improved grate at line xx . Fig. 2 is a plan view showing one-half of the grate-bars in position, the other half omitted, the better to illustrate the parts beneath. Fig. 3 is a sectional elevation view showing in detail the shaking devices. Fig. 4 is a vertical transverse sectional view showing the arrangement of the tilting chairs. Fig. 5 is a plan view of the front bed-beam or supporting-girt, showing two of the shaker-levers. Fig. 6 is a plan view of one end of the grate-bar. Fig. 7 shows the detail of the end guard

or finger-plate in end view, section, and plan. Fig. 8 shows the front of the grate-bar supporter or tilting chair. Fig. 9 is a diagram illustrating the movement of the grate-bar, 55 and Fig. 10 shows a modification.

My improved grate is especially adapted for steam-boiler furnaces of the kind generally employed for stationary boilers and steam-producing plant and can be put in as a part of the original structure or introduced into furnaces to replace grates previously employed therein; also, for other kinds of furnaces wherein a grate of similar nature can be employed. 65

Referring to parts, A A denote the bed-beams or girts upon which the gate-bars B are supported by means of the stilts or tilting chairs C. Said beams are supported upon suitable side frames D, or in some instances, 70 as where furnace-walls are formed of brick, they can be extended into and supported by the brick-work at the sides of the ash-pit. The bed-beams are formed of two longitudinal vertical plates or webs connected together 75 by a series of transverse plates or bars a , having angular-shaped depressions in their upper edges, and upon which the tilting chairs C are seated. The forward bed-beam is provided with a series of lugs or brackets a' , that project 80 forward and are fitted with vertical openings in which are pivotally supported the horizontally-oscillative compound bell-crank levers or shakers E, each of which is provided with a downwardly-projecting pivot for fitting into 85 the opening in the lug a' , and with two upright studs or wrist-pins e , that respectively engage transverse slots in the under side of the grate-bars. Each shaker connects with two adjacent grate-bars in such manner that 90 one bar is drawn forward while the other is moved back, and vice versa, as the shaker or bell-crank lever is oscillated.

An arm E', projecting from the side of the shaker E, is connected by a rod G with a hand-lever G' at the exterior of the furnace wall, by means of which lever the operation of the grate can be effected. The movement of the shakers E in one direction is indicated by dotted lines in Fig. 5, and they swing to the same extent 100 in the opposite direction. Said lever G' is herein shown as fulcrumed on a stud g on the

furnace-front, to be worked by backward and forward swinging of the upper end of said handle-lever.

The shakers or compound bell-crank levers

5 E can be worked singly, if desired, but are best coupled in pairs or in greater numbered series by means of arms e' and link-rods f , so that the grate-bar surface can be operated in sections of two, four, six, or more bars with 10 one handle lever or operator.

The operator or lever G' can be placed at any convenient position, either at the front or side of the boiler-frame or brick-work; or, if desired, in some instances connection can 15 be made with the parts E through the ash-pit door by an arm or connecting-socket, as indicated by dotted lines at E^3 , Fig. 5.

At the ends of the grate-bars B, I provide 20 peculiar stationary guards or finger-plates I, formed substantially as indicated in Figs. 1, 2, and 7, and made in width to correspond with the width of the grate-bars. Said guards are supported on auxiliary bars or bearers H, extending laterally across the space at the 25 front and rear of the furnace. Said guard-plates I are transversely grooved on their under side to fit onto their bearers H, and are furnished with a series of fingers i , arranged to correspond with and lap over the fingers 30 b , formed on the end of the grate-bars. (See Figs. 2, 6, and 7.) The ends of the grate-bars are made with a downward curve, as at F, approximately corresponding to the line of movement of the grate action, and the under part 35 of the guard-fingers are curved upward or inclined to match the same. This curved form at the ends of the bars is designed to prevent clinkers and pieces of coal from entering between the adjacent surfaces of the grate and 40 guard-fingers and there wedging or interfering with the free action of the mechanism.

By constructing the end guards or finger-plates I in sections that correspond in width to the width of the grate-bar any guard-section 45 can be individually removed by simply lifting it from the bearer-bar H, thus giving access to any one of the several grate-bars, which can then be readily and singly removed and replaced, as desired. This finger-plate 50 or removable end guard-section is an important feature of my invention.

J indicates the hearth-plate at the door of the furnace, and K the furnace-front, which can be of any of the usual well-known kinds 55 employed in boiler-furnaces or similar furnace constructions.

The tilting chairs or struts C, by which the grate-bars are sustained, are made, as shown, with two top bearing-surfaces $c c'$, (see Fig. 60 8,) that engage with recessed lugs $n n$ on the interior or between the web-flanges of the grate-bars B, and with two bottom bearing-surfaces $c^2 c^3$, that rest upon the separate 65 cross-bars a of the bed-beam A. The disposition of these four bearing-points gives great lateral width to the chair C, so that the grate-bar is strongly supported against lateral

pressures or sidewise displacement. The lower ends of the tilting chairs are best provided with downwardly-extending lugs X, 70 that engage between the cross-bars a and prevent the chairs from slipping out of place sidewise. The pair of tilting chairs are best disposed beneath the several grate-bars in oppositely-inclined positions, so that as the bar is reciprocated they swing alternately to a vertical position and to an extreme inclined position, thus raising one end of the grate-bar some three-fourths of an inch above the normal level, while the other end is depressed about three-fourths of an inch below the level, and vice versa, effecting an up-and-down action in connection with the endwise movement when the grate-bars are moved either way from their central position, thus giving two 80 distinct movements—viz., horizontal and (see full lines and dotted lines, Fig. 9.)—and thereby causing the fire-bed to be moved bodily and thoroughly shaken.

If in any instance it is desired that the 90 grate-bars should have a straight horizontal movement, the chairs or struts can be formed, as in Fig. 10, to have a segment of a circle at their upper ends, with three or more lugs or teeth thereon to engage with a straight rack 95 on the grate-bar, all other parts of the mechanism being and operating substantially as above described.

I am aware that furnace-grate bars have heretofore been arranged in different manner 100 to have tilting supporters and independent endwise action of the individual bars; and I do not therefore broadly claim such feature irrespective of the particular construction of mechanism as of my invention.

I claim—

1. The combination, with the bed-beams and longitudinally-movable grate-bars, of the tilting chairs sustaining said grate-bars at or near their respective ends disposed at opposite inclinations, so as to alternately swing to a vertical position, the compound bell-crank levers pivoted in brackets on the forward bed-beam and having forwardly-projecting wrist-pins that engage with transverse slots in the 110 grate-bars in a manner to permit up-and-down movement simultaneous with their endwise action, a connection extending to the exterior of the furnace, and a hand-lever attached to said connection for working the bell-crank levers, substantially as set forth.

2. The combination, substantially as described, of the two bed-beams A, the front one provided with the projecting brackets or lugs a' , the compound bell-crank levers E, having downwardly-projecting pivots supported in openings in said brackets, upwardly-projecting wrist-pins e' integral therewith, and operating-arms e' , the grate-bars B, having transverse slots that engage said wrist-pins, the 125 oppositely-inclined tilting chair C, seated on said bed-beam and individually sustaining the respective ends of said grate-bars, the operating-links f , connecting the arms e' , the 130

connecting-link G for moving said bell-crank lever, and the handle-lever G' at the exterior of the furnace, all substantially as and for the purposes set forth.

- 5 3. In a furnace-grate, the end guard I of the peculiar construction shown, comprising the series of fingers i, substantially horizontal on top and forwardly tapered below, the several fingers laterally connected to each other by a transverse undergrooved body, and the transverse auxiliary bearer-beam disposed across the furnace at the ends of the grate, whereon said end guards are sustained by the lip of the body-groove, in combination with the endwise-movable grate-bars having correspondingly-disposed fingers that extend beneath the respective guard-fingers in the same upright planes therewith, all substantially as shown and described.
- 10 4. The end guard-plates formed in sections corresponding in width to the width of the individual grate-bars, and the auxiliary transverse bearer-beams whereon said guard-plates are removably supported, disposed across the furnace beyond the ends of the grate-bar, in combination with the endwise-movable grate-bars having fingered ends that extend beneath said guard-plates, substantially as set forth.
- 15 5. The tilting chair C, when constructed as hereinbefore described, with two upper bear-
- ing-surfaces c and c' and the lower bearing-surfaces c² and c³, and the downwardly-extending lugs X, in combination with the bed-beam having the cross-bars a, recessed to receive said lower bearing-surfaces, and the grate-bars having recessed bearing-lugs n, adapted to receive said upper bearing-surfaces, all substantially as shown and described. 35
6. The combination, as described, of the grate-bars having the ends thereof constructed with a series of longitudinal fingers b, formed with a downward curve on their upper surface, as at F, the end guard-plates having a series of overlying fingers i, disposed in the same upright planes with said grate-bar fingers and undercurved beneath along their overlying ends to match said curve F, the oppositely-inclined tilting chairs supporting 40 said grate-bars and adapted to swing to vertical positions at one limit of their action, and mechanism for moving the grate-bars endwise alternately in opposite directions, substantially as and for the purpose set forth. 50

Witness my hand this 12th day of August, 55
